TRIM PANEL FOR A CARD HOLDER AND RECESSED DRAWER PULL

John E. Foster, Angola, and Donald J. Rendall, Lake-
wood, N.Y., assignors to Weber-Knapp Company,
Jamestown, N.Y., a corporation of New York

Filed July 29, 1965, Ser. No. 86,349

Term of patent 14 years

(Cl. D33—19)

Fig. 1.

Fig. 3.

Fig. 5.

Fig. 2.

Fig. 6.

Fig. 4.

Fig. 7.

Fig. 9.

Fig. 8.

Fig. 10.

Fig. 11.

Fig. 12.

FIG. 1 is a perspective view of a trim panel for a card holder and recessed drawer pull, embodying one form of our new design, this view being from the front and left of the article.

FIG. 2 is a front elevational view thereof.

FIG. 3 is a top plan view thereof.

FIG. 4 is a bottom plan view thereof.

FIG. 5 is a left end view thereof.

FIG. 6 is a right end view thereof.

FIG. 7 is a perspective view of the panel of FIG. 1 wherein same is narrower and longer and the contrastingly colored center strip is wider.

FIG. 8 is a front elevational view thereof.

FIG. 9 is a top plan view thereof.

FIG. 10 is a bottom plan view thereof.

FIG. 11 is a left end view thereof.

FIG. 12 is a right end view thereof.

We claim:

The ornamental design for a trim panel for a card holder and recessed drawer pull, substantially as shown.
